Chicago, Ill., a corporation of Delaware

Application August 17, 1942, Serial No. 455,106

12 Claims. (Cl. 164—112)

This invention pertains to perforating and printing apparatus and more particularly to a combination perforating and printing unit for perforating tape in signal code combination form and substantially simultaneously printing thereon characters representative of the particular permutations punched in the tape. It relates to a manual keyboard perforating and printing device for a tape to be later transmitted at the sending station.

It is known in the field of printing telegraphy that the speed of operation of printing telegraph systems is necessarily limited by the speed of signal transmission and/or reception. Normally, printing telegraph apparatus is operated at a rate of speed considerably less than the rate of speed susceptible of attainment by a competent typist. It is desirable in some cases that tape messages be prepared locally by an operator for subsequent transmitting purposes. For these tape messages, which are locally prepared, it is obviously not necessary that the typing speed of an operator should be limited by signal speed and it is therefore proposed by the present invention to provide a power operated printing and perforating unit controllable from a free keyboard, the operation of which is unrestrained by signal speed requirements. An attendant advantage of such a unit is that it may be operated by a typist who possesses only ordinary typing experience. In the employment of the type of printing telegraph apparatus as exemplified by Patent No. 2,255,794 issued to R. A. Lake on September 16, 1941, and Patent No. 2,273,910 issued to C. W. Swan on February 24, 1942, wherein there are limitations in speed of operation as explained, operators are required who first must be trained before they develop the technique necessary to enable operation of a telegraph keyboard with maximum efficiency.

The primary object of the present invention is the provision of a combined printing and perforating apparatus in which the printing and perforating operations are controlled simultaneously from a keyboard wherein the rate of operation is not limited by the speed of transmission and/or reception of telegraph code signal impulses.

Other objects, features, and advantages of the invention will become evident as the invention is herein further described in more detail.

The present invention provides a keyboard operated printing and perforating mechanism in which tape is perforated dependent on the permutative setting of a series of levers in accordance with the Baudot five-unit code. The set-

ting up of a selection for perforating a tape from the keyboard also causes the simultaneous conditioning of a selector mechanism for enabling substantially concurrent printing upon the same tape and the actual printing and perforating operations are completed by means of cam mechanisms associated with a power driven shaft. During each depression of a key, a universal bar is operated to close a pair of contacts and thus to complete a circuit to a clutch magnet which renders a single revolution clutch effective for initiating the release of the cam mechanisms for a cycle of operations.

The invention may be better understood by reference to the herein following description and to the drawings wherein:

Fig. 1 is an end elevational view, partly in section, of the apparatus embodied in the present invention;

Fig. 2 is a front elevational view of the same apparatus shown in Fig. 1;

Fig. 3 represents a plan view of the proposed apparatus;

Fig. 4 illustrates a tape prepared according to the present invention;

Fig. 5 is a view of the apparatus taken on the line 5—5 of Fig. 3; and

Fig. 6 is a diagram of a circuit provided to prevent repeat operations while causing one cycle operations.

Referring now to the drawings, the invention will be described in more detail. The perforating mechanism now about to be described, is as regards the keyboard, permutation code bars, and punch selectors of the type shown in Patent No. 1,884,753 to H. L. Krum, and reference may be had to that patent for a more complete disclosure of the operating details.

A base casting 11 houses a plurality of key levers 12 each provided with a keytop 13 (Fig. 1). Near the front of the casting and disposed beneath the key levers 12 there is provided a plurality of pairs of code bars 14. The particular number of permutation bars necessary is dependent upon the particular code employed. The structure disclosed in the drawings is adapted for use in a five-unit code and consequently a corresponding number of pairs of code bars is provided. Each pair of code bars comprises a bar 15 and a bar 16. Each of these bars is provided with a pair of vertical slots 17 (Fig. 2), one at each end, by means of which the respective bars are mounted for slidable vertical movement upon the comb members 18 and the end comb members 19.

There is associated with each pair of code bars,

T-shaped rock arms 19 which are pivoted at 6 in the comb members 18 and are provided with offset lugs 20 and 21 which extend in opposite directions. One of the lugs of each rock arm projects forwardly into a notch on the lower edge of the corresponding code bar and its other lug projects rearwardly beneath the companion code bar of the particular pair. Because of this parallelogram arrangement, the depression of either code bar of a pair of bars rocks the T-shaped members 19 and lifts the companion code bar of the particular pair. Articulated to the depending portion of each of the T-shaped rock arms 19 is a longitudinally movable permutation bar 22. When a code bar of any pair is depressed through the action of the key lever, the rock arm arm 19 will be rocked about its pivot, thus moving the longitudinal permutation bar 22 either to the right or left as viewed in Fig. 2.

Each of the key levers 12 may, when operated, engage and depress one of the code bars of each pair of code bars 14 to set these bars in accordance with a character code combination. For the accomplishment of this result the upper edges of the code bars 14 are notched to provide high and low portions in accordance with the particular code. Also, the bars of each pair of code bars are complementary; that is, the notches of one bar are opposite the projections of its companion bar. The interconnection between the bars of each pair of bars 14 by means of the rock arms 19 prevents the simultaneous depression of two key levers. If an attempt is made to operate more than one key lever, the key levers can only be depressed for a short distance when they will be blocked by the high portion of the code bars.

Each permutation bar 22 is provided with an upstanding bifurcated member 23. Interposed between the vertically extending arms of each bifurcated member is a depending portion 24 of one of a series of five vertical levers 25 which are pivoted about the shaft 26. By means of this arrangement, the vertical levers 25 are adapted to be positioned in accordance with the positions assumed by the permutation bars. To each of the vertically extending levers 25 there is pivotally connected at 27 a horizontally extending interponent member 28, the front portion of which is provided with a cut-out section 29 by means of which those interponents 28 which are not shifted to the left (as viewed in Fig. 2) by their associated vertical levers 25 are allowed to remain out of the path of punch pins 32 operable by a punch bail 31 to be hereinafter described in detail. It is now readily understandable that in accordance with the depression of a particular key lever by means of the permutation bars 22, the interponents 28 will be shifted to the left or the right in accordance with the particular code combination associated with the particular key lever. The interponents will thus be selectively positioned for engagement with a series of tape punch pins 32 carried by a punch block 33 when punch bail 31 is operated.

The punch bail 31 includes a cradle portion 34 over which the interponents 28 are mounted for slidable horizontal movement. The punch bail 31 is pivotally mounted about the pivot studs 35 and 36, as best seen in Fig. 1. The cradle portion 34 of the punch bail 31 carries an upwardly extending projection 37 in order that the feed hole of the tape may be invariably punched.

For initiating the operation of the power operated mechanisms of the present invention, each

key lever is permitted to engage a universal bar 38 (Fig. 1) which pivots a pair of associated T-levers 39 (only one being shown) about the shaft 6 to thereby cause the shifting of longitudinal bar member 42 to its right-hand position as viewed in Fig. 2 to close a pair of universally operated contacts 43. The universally operated contacts 43 control a circuit to a clutch magnet 44 (Fig. 3) which in turn controls the operation of a clutch 45. By means of worm gear 46, a motor 47 continuously drives gear 48 carried by fixed sleeve 60 at a faster rate than the selector cam drum of the above-mentioned Lake and Swan patents and thus causes the continual rotation of a shaft 49 to which is operatively connected the driving portion 50 of the clutch 45. Slidably mounted at the upper end of shaft 49 about a sleeve member 51 is a sleeve member 51 which constitutes the driven portion of the clutch mechanism. The sleeve member 51 includes a collar portion 52 engageable by a compression spring 53, which at its opposite end engages the cam member 54 which is integral with sleeve 40 attached to sleeve 51 and thus there is exerted upon the sleeve 52 an upward pressure as viewed in Fig. 1 due to the influence of spring 53. Axial movement of sleeve member 51 is permitted due to the splined connections 55, 56, provided between the sleeve member 51 and the sleeve member 40 positioned therebelow which carries the previously identified cam member 54.

Sleeve 51 is slidably mounted upon the shaft 49 and has a lower splined connection shown generally at 80 to sleeve 59 which is loosely mounted about sleeve 60. A compression spring 30 positioned between collar 58 which is an integral part of sleeve 51 and disc 59, tends to urge sleeve 51 to an upward position while the interposition of a friction disc 100 between the upper side of gear 48 and the lower side of sleeve 59 tends to rotate the sleeve 51 in the same direction as the gear 48 to thereby facilitate the engagement of the teeth of clutch sleeve 51 with the teeth of clutch sleeve 50, and to prevent backing up with consequent grinding of teeth during the disengaging period.

When the clutch magnet 44 is energized upon the depression of the universal bar 38 as each key lever is operated, armature 62 is attracted, the projection 63 of clutch trip lever 64 is removed from the path of the cam stopping surface 9 (Fig. 1) carried by the sleeve member 51, and the spring 53 therefore is enabled to shift the sleeve member 51 to cause its interengagement with the driven clutch member 50. This causes the rotation of the cams for a cycle of operations.

At the lower end of sleeve 51 is carried a punch cam 65 which is engageable by a follower 66 carried by punch arm casting 67. The punch arm casting 67 is pivoted about pivots 68 and 69 and is urged into following engagement with cam 65 by means of a spring 71 which urges punch arm 67 about its pivots 68 and 69 in a counterclockwise direction as viewed in Fig. 2. Pivotally connected to the punch arm 67 about a pivot stud 72 is a punch bail link 73 made up of two elements 74 for adjustability which are interconnected by means of adjusting screws 81. Punch bail 73 is pivoted about a stud 75 at the upper end of punch bail 31. It will now be seen that when the universal bar is operated upon the depression of a particular key, the clutch magnet will allow the release of the cam sleeve 51 and operation of cam 65 whose high portion will engage the follower 66 to rock the punch arm 67 in a clock-

wise direction, as viewed in Fig. 2, causing the punch bail 31 to be likewise rocked in a clockwise direction through the link 73 to enable the operation of punch pins 32 by those interponents 28 which have been shifted to the left, as viewed in Fig. 2, in the particular code combination.

Extending from the cradle portion 34 of punch bail 31 is a projection 82 carrying a pivot 83 adapted to support a feed pawl 84 which operates the tape feed roll 85 to cause the advancement of the tape for each cycle of operation. On each operation of the punch bail 31, the feed pawl 84 will be raised and lowered to cause the stepping of feed roll 85 in a manner well known in the art.

Punch block 33 herein disclosed is adapted to punch chadless tape which is a kind of tape wherein a series of hinged lids are punched in the tape rather than a complete circular perforation. This feature is described in detail in the above mentioned patent to R. A. Lake, and reference may be had to such patent for a detailed disclosure. A section of chadless tape prepared in accordance with the present invention is shown in Fig. 4.

Printing operation

Mounted on pivot shaft 91 (Fig. 2) is a bell crank bail member 92 having a bifurcated extension 93 engageable by pin 94 carried by the punch bail 31. The opposite arm 95 of the bell crank member carries an upwardly projecting portion 96 which underlies a series of five horizontal levers 97 also mounted on the pivot shaft 91. The upper portion of vertical levers 25 which are positionable according to the particular code combination effected by the depression of a particular key are positionable to underlie or to remain out of the path of the horizontal levers 97. When the punch bail 31 (Fig. 2) is pivoted in a clockwise direction as explained, the engagement of pin 94 associated with the punch bail in the bifurcation 93 of bell crank 92 withdraws the projection 96 associated with the bail 92 from beneath the horizontal levers 97 inasmuch as clockwise pivotal movement is also imparted to the bail member 92 due to the engagement of pin 94 in the bifurcation 93. It is thus apparent that those levers 97 which are not blocked by associated vertical levers 25 will be free to pivot downwardly in a clockwise direction as viewed in Fig. 2. Mounted adjacent the horizontal levers 97 as best seen in Fig. 1 are a series of five bell cranks 98 pivotally mounted upon a common shaft 99. The horizontally extending arms 101 of the bell cranks 98 are of progressively arranged lengths and carry depending portions 102 each adapted to make contact with an associated horizontal lever 97. The upwardly extending arms 103 of the bell cranks 98 are adapted to contact a series of five vertical levers 104 all pivotable about a common shaft 105. The vertical levers 104 are of progressive lengths as best viewed in Fig. 2, and are adapted to cooperate with a series of five bell cranks 106 also having arms 107 of complementary progressive lengths, the bell cranks being mounted about a common pivot 108. To projections 109 and 111 of each of the bell cranks 106 are attached, respectively, springs 112 and 113 which urge each of the bell cranks 106 in a clockwise direction, as viewed in Fig. 3.

Mounted adjacent to the arms 114 of each of the bell cranks 106 is one of a series of five code bars 115. Each of the code bars 115 has formed thereon a slotted portion 116 into which projects the extremity of one of a series of five levers 117 which are urged in a counterclockwise direction

by means of springs 118 and 119 about a common pivot point 121. Also mounted about the pivot point 121 is a bail member 122 having an integrally formed arm 123 which carries a projecting extension 124 adapted to straddle all of the levers 117. An arm 125 of the bail 122 carries a follower 126 which engages a code bar release cam 54 carried by sleeve 40. A spring 127 urges the follower roller 126 of bail member 122 into engagement with the cam 54. At the proper time in the operating cycle, cam 54 will act to withdraw projection 124 from blocking engagement with levers 117.

Simultaneously, therefore, with the setting of the vertical levers 25, the horizontal levers 97 will either be blocked or unblocked according to the particular permutation, so that when punch bail 31 is operated, the bail 92 will withdraw its projection 96 from beneath the horizontal levers 97, and those horizontal levers which are not blocked will be permitted to pivot in a clockwise direction as viewed in Fig. 2. The freeing or unblocking of a particular horizontal lever 97 allows its associated bell crank 98 to pivot in a counterclockwise direction as viewed in Fig. 1 and further enables the clockwise pivotal movement of a particular vertical lever 104 and the clockwise pivotal movement of its associated bell crank 106, as viewed in Fig. 3, under the influence of springs 112 and 113. When the clutch assembly is released for rotation as magnet 44 becomes energized as previously explained, cam follower 126 rides upon a high portion of cam 54 and the extension 124 of the bail 122 is removed from the path of the levers 117 and springs 118 and 119 are enabled to operate levers 117 to shift their associated code bar to the right as shown in Fig. 3, if they are not blocked at this time by arms 114 of these bell crank levers 106 which have been freed for clockwise pivotal movement, as viewed in Fig. 3. If the vertical lever 104 is free for pivotal movement as already explained, its associated bell crank 106 is permitted to move in a clockwise direction under the influence of springs 112 and 113. The code bars 115 therefore will be permutably conditioned in accordance with the particular combination effected by the depression of a particular key lever. In the rest position of cam 54, the extension 124 of bail 122 acts to restore levers 117 and code bars 115 to their original positions.

The printing mechanism about to be described is shown in detail in the patent to Morton et al., No. 1,745,633, and reference may be had to such patent for a detailed description thereof. The particular setting of the code bars 115 enables one of a series of pull bars 131 to fall into a recess provided by the vertical alignment of a series of notches of the code bars adjacent the selected pull bar. This is accomplished under the influence of a spring 132 associated with each pull bar. Each pull bar 131 has formed thereon a projection 133 which is engageable by a bail member 134 carried upon a bail plunger 135 when the bail plunger is raised to its upward position as will hereafter appear. At the lower end of pull bars 131 there is formed a rack portion 130 adapted to engage with a pinion portion 137 of a type bar 138. When, therefore, the bail 134 engages the projection 133 of a particular pull bar 131, the pull bar is raised, and through its rack portion 136 causes the pivotal movement of its associated type bar 138 whose type carrying member 139 strikes a ribbon (not shown) positioned above the tape and platen 140 which are

in the path of the actuated type bar, thus causing a printing impression to be made upon the tape. In operation of the proposed unit, the perforated permutations in the tape will be six spaces from their associated printed representation so that a particular portion of a message can be readily found by an operator and the message may be conveniently inserted into a telegraph transmitter for transmitting purposes.

Motion is imparted to the bail plunger 135 (Fig. 5) by means of a cam 141. Mounted about a shaft 142 is a lever 143 and a lever 144, the lever 143 being urged toward an adjustable screw 145 carried by the lever 144 by means of a spring 146 and thus the levers 143 and 144 are designed to move as a unit. At the proper time in the operating cycle, a follower 147 associated with lever 144 will reach a drop-off portion of the cam 141, and under the influence of spring 146 the lever 143 will be pivoted. Due to the engagement of the extremity of lever 143 in the slot 148 of the bail plunger 135, the bail plunger will be raised to its vertical operating position to effect a printing or operating function.

In order to prevent a repeat operation of a character which may occur when an operator retains a finger on a particular key for too long a period of time, there is provided in Fig. 6, a simple nonrepeat circuit. When clutch magnet 44 is energized upon the operation of universal contacts 43, code release cam 54 will rotate, as explained, to pivot bail 122 in a counterclockwise direction as viewed in Fig. 3. Attached to arm 125 of bail 122 is a pin 201 which causes the closure of a contact pair 202 under the just mentioned conditions. This causes a momentary energization of a nonrepeat relay 203 over an obvious circuit and a consequent momentary attraction of tongues 204 and 205 associated therewith. If the operator has not at this time removed the finger from the particular key which was operated, such procedure will not cause continued energization of magnet 44 because by so doing battery will be supplied through the universal contact 43 and tongue 205 to nonrepeat relay 203 causing tongue 204 to maintain an open circuit condition to clutch magnet 44 until the operator releases the key.

It is thus seen that by the present arrangement there is provided a combined keyboard perforating and printing unit in which the depression of a particular key of the keyboard causes almost simultaneously the perforating of the tape and the printing thereon of a printed characteristic of the code combination which has been perforated in the tape.

Numerous changes and modifications may be made in the proposed construction without departing from the spirit and scope of the appended claims.

What is claimed is:

1. A combination tape perforator and printer comprising tape punching instrumentalities, a punch selector mechanism for permutably selecting said instrumentalities, a keyboard for directly operating said selector mechanism, a tape printing mechanism, a type selector mechanism for controlling said printing mechanism in accordance with the setting and under the sole control of said punch selector mechanism, and power means for operating said punching instrumentalities and said printing mechanism to thereby effect a combined tape printing and perforating operation on a tape.

2. In a combination tape perforator and printer, tape punching instrumentalities, a punch selector mechanism for permutably controlling said instrumentalities, a keyboard for directly controlling said punch selector mechanism, a tape printing mechanism, a type selector mechanism for controlling said printing mechanism, transfer means for transferring a selection established by said punch selector mechanism directly to said type selector mechanism, means associated with said tape punching instrumentalities to effect a tape perforating operation in accordance with the operation of said punch selector mechanism, and means included in said printing mechanism to effect a tape printing operation in accordance with the operation of said type selector mechanism.

3. In a combined tape perforator and printer, a set of tape punching elements, a punch selector mechanism for permutably controlling said elements, a keyboard for controlling said punch selector mechanism, a tape printing mechanism, a type selector mechanism for controlling said printing mechanism, a linkage system for transferring permutations established by said punch selector mechanism directly to said type selector mechanism, and power means for operating said punching elements and said printing mechanism to effect combined tape perforating and printing operation in accordance with the permutations established by said punch selector mechanism.

4. In a combined tape recording and printing apparatus, a set of tape recording elements, a punch selector mechanism for permutably controlling said elements, manually operated means for controlling said punch selector mechanism, a tape printing mechanism, a type selector mechanism for controlling said printing mechanism, means for transferring permutations established by said punch selector mechanism directly to said type selector mechanism, and means for operating said recording elements and said printing mechanism in accordance with the permutations established by said punch selector mechanism to effect a combined tape printing and perforating operation.

5. In a combined tape perforating and printing apparatus, a set of tape punching elements, a punch selector mechanism for permutably controlling said elements, manually operated means for controlling said punch selector mechanism, a tape printing mechanism, a type selector mechanism for controlling said printing mechanism, means for transferring permutations established by said punch selector mechanism directly to said type selector mechanism, means for operating said punching elements, means for operating said printing mechanism, and power operated means for controlling the operation of each of said last-mentioned operating means to thereby effect combined tape perforating and printing operations.

6. In a combined strip perforator and printer, a manually operable keyboard, strip perforating means, a punch selector mechanism for permutably conditioning said strip perforating means which is controlled by said keyboard, strip printing means, a type selector mechanism for permutably conditioning said strip printing means, a lever system interposed between said selector mechanisms which is acted upon by said punch selector mechanism to condition said type selector mechanism, and power mechanism for operating said perforating and printing means.

immediately after they have been conditioned by their respective selector mechanism.

7. In a keyboard controlled recorder, a series of key levers, a punch selector mechanism controlled by said key levers, a plurality of type elements, a type selector mechanism for selecting said elements for operation, a lever system interposed between said selector mechanisms whereby said type selector mechanism is controlled by said punch selector mechanism through the instrumentality of said lever system, and power means for operating said type elements after they have been selected.

8. In a keyboard controlled recorder, a series of key levers, a punch selector mechanism controlled by said key levers, a plurality of type elements, a type selector mechanism for selecting said type elements, means to limit the performance of said recorder invariably to a single operation upon each actuation of a key lever, an electrical contact associated with said type selector mechanism, means to automatically close said electrical contact upon operation of said type selector mechanism to operate said limiting means at predetermined times so as to establish a nonrepeat circuit during a cycle of operation of said type selector mechanism, a lever system interposed between said selector mechanisms whereby said type selector mechanism is controlled by said punch selector mechanism by means of said lever system, and power means for operating said type elements after they have been selected.

9. In a combined perforator and printer, a manually operable keyboard, a plurality of keys, perforating means, mechanism for controlling selectively said perforating means comprising a plurality of permutation bars operated by said keys and a plurality of interponents operated by said permutation bars to condition said perforating means for operation, printing means, mechanism for controlling selectively said printing means comprising a plurality of code bars and a plurality of levers engaging said code bars to condition said printing means for operation, a lever system interposed between said mechanisms whereby said mechanism for controlling selectively said perforating means controls said mechanism for controlling selectively said printing means through said lever system, a cam actuated bail to unlock said levers at predetermined times for movement in accordance with the operation of said lever system, and cam actuated means for operating said perforating and printing means after they have been selected.

10. In a combined perforator and printer, a manually operable keyboard, a plurality of keys, perforating means, mechanism for controlling selectively said perforating means comprising a plurality of permutation bars operated by said keys and a plurality of interponents operated by said permutation bars to condition said perforating means for operation, printing means, mechanism for controlling selectively said printing means comprising a plurality of code bars and a plurality of levers engaging said bars to condition and printing means for operation, a

lever system including a plurality of blocking instrumentalities, one individual to each code bar interposed between said mechanisms whereby said mechanism for controlling selectively said perforating means controls said mechanism for controlling selectively said printing means through said lever system, means effective to govern permissively the positionment of said plurality of levers to impart to said code bars movements in accordance with the settings of said instrumentalities, and means for operating said perforating and printing means after they have been selected.

11. In a combined perforator and printer, a manually operable keyboard, a plurality of keys, perforating means, mechanism for controlling selectively said perforating means comprising a plurality of permutation bars operated by said keys and a plurality of interponents operated by said permutation bars to condition said perforating means for operation, printing means, mechanism for controlling selectively said printing means comprising a plurality of code bars displaceable in accordance with the setting of said permutation bars to condition said printing means for operation, a lever system interposed between said mechanisms, means effective to govern permissively the positionment of the levers of said lever system in accordance with the setting of said permutation bars whereby said mechanism for controlling selectively said perforating means controls said mechanism for controlling selectively said printing means, and means for operating said perforating and printing means after they have been conditioned.

12. In a combined perforator and printer, a manually operable keyboard, a plurality of keys, perforating means, mechanism for controlling selectively said perforating means comprising a plurality of permutation bars operated by said keys and a plurality of interponents operated by said permutation bars to condition said perforating means for operation, printing means, mechanism for controlling selectively said printing means comprising a plurality of code bars displaceable in accordance with the setting of said permutation bars and a plurality of levers engaging said code bars to condition said printing means for operation, a lever system including a plurality of blocking instrumentalities, one individual to each code bar interposed between said mechanisms whereby said mechanism for controlling selectively said perforating means controls said mechanism for controlling selectively said printing means through said lever system, means effective to govern permissively the positionment of the components of said lever system in accordance with the setting of said permutation bars, means effective to govern permissively the positionment of said plurality of levers to impart to said code bars movements in accordance with the setting of said instrumentalities, and means for operating said perforating and printing means after they have been conditioned.

CERTIFICATE OF CORRECTION.

Patent No. 2,343,882.

March 14, 1944.

JOHN O. CARR, ET AL.

It is hereby certified that error appears in the printed specification of the above numbered patent requiring correction as follows: Page 5, first column, line 67, claim 10, for "and" read --said--; and that the said Letters Patent should be read with this correction therein that the same may conform to the record of the case in the Patent Office.

Signed and sealed this 30th day of May, A. D. 1944.

Leslie Frazer

(Seal)

Acting Commissioner of Patents.
